UNITED STATES PATENT OFFICE

ARTHUR R. ANDERSON, OF NORTH ARLINGTON, NEW JERSEY

SHOE TREE

Application filed November 14, 1929. Serial No. 407,224.

The present invention relates to improvements in shoe trees.

More particularly the invention relates to improvements in shoe trees of the so called "full tree" type embodying a toe section and a heel section united by an adjustable pivotal connection for permitting adjustment between the toe and heel sections for readily varying the length of the tree for fitting different size shoes.

10 Shoe trees of this general character have heretofore been proposed, but in the previous constructions the toe and heel sections were constructed for the association therewith of the adjustable pivotal connection in such manner that considerable time and labor was entailed in the construction thereof, thus resulting in a relatively expensive shoe tree.

20 It is accordingly a primary object of the present invention to provide a shoe tree which is simple in construction, easily adjusted and capable of being manufactured rapidly at a relatively low cost.

25 It is a further object of the invention to provide a shoe tree of the so called "full tree" type embodying toe and heel sections having an adjustable pivotal connection associated therewith and concealed in such manner as 30 not to effect the external appearance of the tree and to render the adjusting device impossible of manipulation when pressing the tree in a shoe.

With these objects in view as well as others 35 that will become apparent during the course of the following disclosure reference will be had to the accompanying drawings forming part of same and in which:

Figure 1 is a top plan view of the shoe tree 40 in its shortest adjusted position.

Figure 2 is a vertical longitudinal sectional view taken substantially on line 2-2 of Figure 1 showing the heel section swung outwardly in dot and dash lines.

45 Figure 3 is a transverse sectional view on line 3-3 of Figure 2.

Referring to the drawings by reference characters in which like characters designate like parts, 10 designates the toe section and 11 designates the heel section which sec-

tions jointly form the shoe tree proper. The toe section 10 is of the general configuration of the toe portion of a shoe and terminates at the rear end thereof in an inclined surface 12 at a point approximating the shank of 55 the shoe which surface substantially abuts a similarly inclined front end surface 13 of heel section 11 in the shortest adjusted position of the sections as indicated in Figures 1 and 2 thus providing a full toe and a full 60 heel section in this position. The toe section 10 is provided with a plurality of longitudinal slits 14 which not only provide an ornamental appearance but also provide for ventilation whereby a shoe may dry out should the tree be inserted therein when the shoe is 65 damp. The slits 14, as will be more clearly seen from Figure 2, are formed by a circular saw whereby the slits may be formed with substantially little time and labor. This is 70 an important factor in the manufacture of devices of this character which are sold at a relatively low price.

The sections 10 and 11 on the top thereof and adjacent the opposing ends are provided with arcuate surfaces 16 and 17 respectively, which, as indicated in Figure 2, register in the abutted position of sections 10 and 11. Section 10 is provided with a slit 18 and section 11 is provided with a slit 19 in longitudinal alignment with the slit 18. Slits 18 and 19 are also formed with a circular saw and in the construction thereof due to the relatively small depth of the slits compared to the combined length thereof it is necessary to move the sections longitudinally relative to the saw axis thus providing an elongated slit composed of slits 18 and 19 having the opposite ends thereof of arcuate formation corresponding to the circumference of 85 the saw and a base portion on substantially greater curvature. By forming the slits in this manner substantially little time and labor is required thus further contributing to the production of an inexpensive shoe tree. 90

The heel section 11 is provided with a bore 21 extending through the rear end thereof and opening into slit 19 adjacent the base thereof as indicated in Figure 2. Said bore 95 may be formed in a convenient manner, as

will be obvious. A link 22 of a thickness substantially equal to slits 18 and 19 is pivotally connected at the forward end thereof on a pin 23 which is driven through a transversely disposed bore 23' in section 10 extending through slit 18. The rear end of link 22 is reduced in width providing a substantially narrow guide section 25 slidably disposed in bore 21. The link 22 is provided with an elongated slot 27 having a plurality of longitudinally spaced circular recesses 26 opening into said slot the recesses 26 and slot 27 providing for a range of convenient adjustment between sections 10 and 11 as well as providing for the maintenance of the sections in any adjusted position by the cooperation with recesses 26 and slot 27 of a mechanism about to be described.

Heel section 11 is provided centrally thereof with a substantially small bore 29 intersecting slit 19. Said bore 29 merges into an enlarged circular recess 31 at one side of heel section 11 and into a larger circular recess 32 at the opposite side of heel section 11. A pin 33 is slidably mounted in bore 29 and embodies an intermediate section of reduced diameter, which as indicated at 34, is normally positioned to one side of link 22, as shown in Figure 3. Pin 33 is provided with a head 35 on one end thereof which is disposed in recess 31 and normally engages the shoulder formed at the base of recess 31. The opposite end of pin 33 is provided with a reduced extension 36 which engages a corresponding aperture in a disk plate 37, which plate is secured in position by riveting over extension 36 or in any other desired manner. A coil spring 39 is interposed between disk plate 37 and the bottom of recess 32 for normally holding head 35 in engagement with the base of recess 31 and reduced section 34 of pin 33 to one side of link 22. In the latter position the body portion of pin 33 is in engagement with one of the recesses 26 of link 22.

The shoe tree is applied, when in an angular position, as indicated by dot and dash lines in Figure 2, whereupon heel section 11 is pushed downwardly into the shoe into more or less tight engagement therewith. In order to conveniently remove the tree it is provided at the heel section with suitable finger gripping means which in accordance with the present invention comprises a ring shaped member 42 provided with outwardly turned inner ends 43 which are secured for pivotal movement between the top of section 11 and outwardly arched ears 44 formed integrally with or secured to a plate 45 which is attached to section 11 by a screw 46. Ears 44 are provided with substantially long extensions 47 one of which extends vertically in an aperture 48 on each side of slit 19, thereby providing reinforcing means which tend to resist separation of the parts of heel section 11 on opposite sides of slit 19 and bore 21. Ac-

cordingly should the section 11 become broken in the plane of slit 11 and bore 21 due to the weakening thereof by the formation of said slit and bore the parts will still be maintained against separation by extensions 47. 70

In operation of the device disclosed, sections 10 and 11 are adjusted to provide a required length to suit the particular shoe in which the tree is to be inserted, which adjustment is readily effected by pressing inwardly 75 with the thumb or finger on plate 37 against the action of spring 39 thereby moving pin 33 in bore 29 until reduced section 34 is disposed in slit 19 which portion 34 being of a diameter slightly less than the width of slot 80 27 permits movement of link 22 relative to pin 33 as indicated by dot and dash lines in Figure 2, and when link 22 has been moved a sufficient distance to provide the required length of tree pressure on plate 37 is removed 85 whereupon spring 39 will move pin 33 to the position indicated in Figure 3 with the body of pin 33 in engagement with another aligned pair of recesses 26 thus locking link 22 against longitudinal movement relative to pin 33 and holding sections 10 and 11 in longitudinally adjusted position.

It will be seen that sections 10 and 11 are provided with a pivotal connection on pin 23 whereby section 11 may be moved outwardly, 95 as indicated by dot and dash lines in Figure 2, for permitting insertion of the tree in a shoe irrespective of the relative adjusted positions of the sections and the inclined end surfaces 12 and 13 on the respective sections 10 100 and 11 permit this pivotal movement even when said surfaces are in contact or in the shortest adjusted position of the tree as indicated in Figures 1 and 2.

It is to be particularly noted that the pivotal connections and the entire adjusting means are completely housed within the sections 10 and 11 which not only provides a shoe tree having a neat external appearance but by the disposition of the pivoting and adjusting means within the sections as disclosed, the tree is void of any projecting parts which might injure a shoe and furthermore the disposition of the adjusting means within section 11 entirely avoids any possibility 115 of manipulation thereof while pressing the tree within a shoe as plate 37 secured to adjusting pin 33 as is clearly indicated in Figure 3 is normally disposed inwardly of the mouth of recess 32 at such a distance as to 120 avoid pressure engagement therewith by any portion of the shoe.

It will be seen from the foregoing disclosure that a shoe tree is provided which is simple in construction and is capable of being 125 manufactured at a minimum cost and that the sections embodied in the tree are connected for pivotal and longitudinal movement by means substantially completely housed in the sections and that the sections are formed for 130

the reception of said means by simple operations on the material of said sections without the necessity of employing additional parts for accommodating said means, thus 5 providing a shoe tree which can be manufactured at a very low cost by embodying few simple parts thus greatly reducing the liability of breakage and inoperativeness of the device.

10 While I have disclosed but a single specific embodiment of my invention, it is to be considered in all respects as illustrative only and not restrictive, the scope of the invention being indicated by the appended claims rather 15 than by the foregoing description, and all changes which come within the meaning and range of equivalency of the claims are therefore intended to be embraced therein.

What I claim and desire to secure by United 20 States Letters Patent is:

1. A shoe tree comprising co-operating toe and heel sections; said sections provided jointly with a longitudinal slit substantially centrally thereof; said heel section provided 25 with a longitudinal guide opening in the plane of said slit; a link having one end thereof disposed in said slit and pivotally secured to said toe section; the opposite end of said link movably disposed in said guide 30 opening; spring latching means in said heel section; said link provided with means for co-operation with said latching means for effecting longitudinal adjustment between said sections; and reinforcing means detachably secured to said heel section and entering same on either side of said guide 35 opening.

2. The combination defined in claim 1 in 40 which said reinforcing means embodies a plate; and finger gripping means pivotally secured to said plate.

3. A shoe tree comprising toe and heel sections; said toe section provided with ventilating openings; said toe and heel sections 45 jointly provided with a longitudinally disposed slit in the outer faces thereof; said heel section provided with a longitudinally disposed guide opening communicating with said slit; a link comprising a body portion disposed in said slit and a guide portion disposed in said guide opening; said link pivotally secured adjacent one end thereof to said toe section and provided with communicating 50 apertures in the said body portion thereof; spring pressed means in said heel portion cooperating with said apertures for effecting longitudinal adjustment between said sections; and finger gripping means carried by 55 said heel section comprising a loop-shaped member; a plate detachably secured to said heel section and embodying ears between which and said heel portion said loop-shaped member is pivotally disposed; said plate 60 embodying substantially long extensions, one of 65

which extends vertically into said heel section on each side of said slit and said guide opening.

In testimony whereof I affix my signature.
